Primary Examiner — Austin Murphy

(74) *Attorney, Agent, or Firm* — Biotech Beach Law Group PC(57) **CLAIM**

I claim the ornamental design for a finger ring with retractable stylus, as shown and described.

DESCRIPTION

FIG. 1 is a right, front, top perspective view of a right hand version of a finger ring with retractable stylus showing my new design;

FIG. 2 is right side elevational view thereof;

FIG. 3 is a left side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a right, front, top perspective view thereof, showing an alternative position of use, wherein the stylus is depicted in a retracted or closed configuration;

FIG. 9 is right side elevational view thereof;

FIG. 10 is a left side elevational view thereof;

FIG. 11 is a top plan view thereof;

FIG. 12 is a bottom plan view thereof;

FIG. 13 is a front elevational view thereof;

FIG. 14 is a rear elevational view thereof;

FIG. 15 is a left, front, top perspective view of a left hand version of a finger ring with retractable stylus showing my new design;

FIG. 16 is right side elevational view thereof;

FIG. 17 is a left side elevational view thereof;

FIG. 18 is a top plan view thereof;

FIG. 19 is a bottom plan view thereof;

FIG. 20 is a front elevational view thereof;

FIG. 21 is a rear elevational view thereof;

FIG. 22 is a left, front, top perspective view thereof, showing an alternative position of use, wherein the stylus is depicted in a retracted or closed configuration;

FIG. 23 is right side elevational view thereof;

FIG. 24 is a left side elevational view thereof;

FIG. 25 is a top plan view thereof;

FIG. 26 is a bottom plan view thereof;

FIG. 27 is a front elevational view thereof; and,

FIG. 28 is a rear elevational view thereof.

The broken lines shown in the drawings are for illustrative purposes only and form no part of the claimed design.
